UNITED STATES PATENT OFFICE.

VICTOR V. THOMAS, OF CHICAGO, ILLINOIS, ASSIGNOR, BY MESNE ASSIGNMENTS, TO
L. B. TAYLOR, OF CHICAGO, ILLINOIS.

CINEMATOGRAPH.

1,188,114.

Specification of Letters Patent. Patented June 20, 1916.

Application filed September 21, 1914. Serial No. 882,729.

To all whom it may concern:

Be it known that I, VICTOR V. THOMAS, a citizen of the United States, and a resident of Chicago, in the county of Cook and State 5 of Illinois, have invented certain new and useful Improvements in Cinematographs, of which the following is a specification.

My present invention relates to cinematographs and has special reference to the provision of simple and effective mechanism for what is called framing the picture in that variety of cinematograph designed for projecting the picture which employ a strip or ribbon of film which contains a series of 15 chronologically successive views. In such machines the respective views are moved successively into position before an opening where they remain stationary for a brief period of time while a beam of light is 20 thrown through them in order to project the picture. Some expansion or contraction of the film is inevitable which makes it necessary to provide facilities for securing an exact registry of the respective views with 25 the opening or light passage when they are brought into position before it. The securing of the registry between the view and the light opening is known as framing the picture.

30 My present invention is illustrated in the accompanying drawing, in which—

Figure 1, is a side view of the interior of a simple form of cinematograph with my invention embodied therein; Fig. 2, is a central sectional detail of my invention on line 2—2 of Fig. 1, and Fig. 3, is an end view of the swinging arm and mounting or bearing therefor on line 3—3 of Fig. 2.

Similar reference characters refer to similar parts throughout the several views.

The cinematograph is installed in a box or casing, 1, in the top of which is a slot or opening, 2, of suitable shape and size for the entry of the strip or ribbon of film, 3. 45 The strip or ribbon or film is generally provided with sprocket holes or perforations upon the edges thereof and after the entrance into the casing or boxing, 1, it is held by means of a spring pressed roller, 4, against a continuously driven roller, 5, having sprocket teeth, 6, thereon adapted to enter into and engage with the sprocket holes or apertures in the edges of the film strip or ribbon.

55 The driven roller, 5, draws the film into

the boxing, and from this roller the film passes into a loop or bight, 7, between tensioning springs, 8, arranged on each side of the light opening, 9, and a swinging frame, 10; having a central opening mounted inside 60 of the casing, 1, and registering with said light opening.

From in front of the light opening 9 and from the tensioning devices the film passes to an intermittently driven sprocket roller, 65 11, which is similar to roller 5, and which is provided with sprocket teeth, 12, and against which the film ribbon is held by a spring pressed roller, 13, and from the intermittently driven roller, 11, the film passes in 70 another bight or loop, 14, to a continuously driven sprocket roller 15 and spring pressed roller, 16, similar to rollers 5 and 4, and from there the film leaves the casing or boxing, 1, through a suitably disposed slot, 17, and 75 passes to a take up (not shown).

From the foregoing brief description it appears that the intermittently driven roller, 11, draws the pictures into position 80 before the light opening and my present invention comprises the provision of simple and effective facilities for adjusting the film so that the respective pictures on the film strip or ribbon will come to rest in exact register with the light opening. The details 85 of these facilities are shown in Figs. 2 and 3. The intermittently driven roller 11 is secured by means of a set screw 11^a to a shaft 11^b, which is journaled in an elongated bushing 11^c an end of which is assembled by a 90 force bit, or in any other suitable manner, with an aperture 11^d in the side of the casing or boxing, 1. Just inside of the wall of the casing or boxing, 1, the elongated bushing 11^c, is provided with an annular flange or 95 shoulder, 11^e, one side of which contacts the said wall. Fitting about the elongated bushing and against the opposite side of the annular flange or shoulder, 11^e is a split ring rotatable support or hub, 11^f, the ends of which are adjustably drawn together, so as to control the amount of friction between the said ring or hub and bushing, by means of the screw 11^g, and the said hub is held against longitudinal movement on the bushing by means of a collar 11^h fitting around the bushing upon the side of said hub opposite to the annular flange 11^e which said collar is held in position by a set screw 11ⁱ.

Extending radially from the said hub, 11^f, 110

2
is an arm, 11^b, in the outer end of which is a shaft 11^k extending parallel to the shaft 11^b, and upon this shaft, 11^k, is mounted a roller, 11^L, upon which it is held by a washer or washers 11^m and a screw, 11°, which screws into the bored and tapped end of said shaft 11^k. An operating arm 11^p, also extends radially from said hub 11^x to the outside of the box or casing, 1, through a suitable slot provided in a wall thereof.

It will now be seen, especially by reference to Fig. 1 that a movement of the operating arm 11^p will move the roller 11^L into or out of the path of the tensioning device to the 15 intermittently driven sprocket 11 thereby increasing or diminishing the length of film between said tensioning device and said sprocket and thereby controlling the portion of the film which is moved into position before the light opening.

Having described my invention, what I

claim as new and desire to secure by Letters Patent is,—

In a cinematograph having a light opening, means for holding a portion of a film 25 ribbon before said opening, an intermittently driven sprocket for drawing said film therefrom, a rotatable support rotatable about the axis of said sprocket, adjustable means for frictionally securing said support 30 upon its bearing, an arm extending from the said support for rotating the same upon its bearing and a roller carried by said support into and out of the path between said film-holding means and said sprocket. 35

In testimony whereof, I have hereunto set my hand:

VICTOR V. THOMAS.
